UNITED STATES PATENT OFFICE.

HENRY FEYH, OF PHILADELPHIA, PENNSYLVANIA, ASSIGNOR TO GOODELL & WATERS, OF SAME PLACE.

MORTISING-MACHINE.

SPECIFICATION forming part of Letters Patent No. 281,855, dated July 24, 1883.

Application filed May 3, 1882. (No model.)

To all whom it may concern:

Be it known that I, HENRY FEYH, a citizen of the United States, residing at Philadelphia, in the county of Philadelphia and State of Pennsylvania, have invented certain new and useful Improvements in Mortising-Machines; and I do hereby declare the following to be a full, clear, and exact description of the invention, reference being had to the accompanying drawings, which form part of this specification, in which—

Figures 1 and 2 are perspective views. Fig. 3 is an elevation, and Figs. 4 and 5 are sectional detail views of my improvements. 15 My invention has relation to mortising-machines; and my improvements have for their object to provide a construction whereby the following results will be obtained: First, the chisel, when not in operation, will stand in an elevated position above the table, so as to permit the stuff which is to be mortised to be placed upon said table without interference with or impediment from said chisel; second, the extent of stroke of said chisel may be graduated or regulated; third, the jarring or shock 20 heretofore produced in mortising-machines by depressing the treadle is avoided.

My improvements consist in the peculiar construction and combination of parts herein- 25 after fully set forth.

Referring to the accompanying drawings, A indicates the table of a mortising-machine, and B the chisel, which has a vertical movement over the same, derived from a pitman, 30 C, which, through a link, e, and intermediate mechanism, hereinafter described, has motion imparted to it from a shaft, d, carrying an eccentric-wheel, D. From the wrist d' of the eccentric extends a link, E, whose lower end 35 is swiveled on a wrist-pin, f, on a lever, F, which is secured by screws f' f'' to a U-shaped bracket, G. If desired, the lever F and bracket G may be made in one piece. The bracket G has trunnions g g, which have bearings in a fixed frame-piece, H, and these trunnions form the fulcrum of the lever F.

I represents a block, made, preferably, in three pieces, I' I'' I''', having a dovetail groove, i, which receives the lever F, on which latter 40 said block may be slid lengthwise. The block I has two lateral pivot-studs, i i', to

which are attached the lower ends of the link e and the rear end of a toggle-lever, K, respectively. When the studs i i' are aligned with the trunnions g g, the block I has the same center of motion as the lever, and the link e is motionless; but when the said block is slid backwardly toward the pin f said link will be moved up and down, imparting motion to the pitman C, and thereby to the chisel B. 55 The forward end of toggle-lever K is pivoted at k on an extension, h, of the frame-piece H.

L is a treadle, pivoted at l on a stationary bracket, l', and pivotally connected by a link, M, with the toggle-lever K. Said link has an elongated slot, m, through which passes a pin, k', whereby connection is made with the treadle L.

N is a counterbalance-lever, having at one end a weight, n, and at the other a rod, n', whose lower end is connected to the treadle L by the same pin, l'', which connects said treadle with the slotted link m. Normally, the weighted lever N holds the treadle in the position indicated in dotted lines in Fig. 3, at which time 75 the slide I is centered with the lever F and no motion is communicated to the chisel. When, however, the treadle is depressed, as shown in full lines, the toggle becomes straightened out or extended, sliding the block I back on the 80 lever F, causing it to vibrate vertically with said lever, and thus communicate motion to the chisel through the link e and pitman C. The extent of movement of the chisel is governed by the distance which the block is moved 85 backwardly on the lever, and this in turn depends on the distance the treadle is depressed by the operator. To cause the chisel to operate, therefore, the workman depresses the treadle with his foot, and upon releasing 90 pressure on the treadle the latter is lifted by the weight n, causing the parts to resume their normal position and the chisel to cease moving, the latter stopping in an elevated position above the table. In depressing the treadle L 95 the pin k' traverses the slot m in the link M, and thereby causes the shock or jar which would otherwise be felt by the workman to be avoided.

What I claim as my invention is—
1. In a mortising-machine, the combination 100 of the lever F, connected at one end to the pit-

- man E and at the other to the U-shaped bracket G, said bracket being journaled, as shown at *g g*, with the sliding block I, connected to the treadle L by toggle K and link 5 *m*, and to the pitman C by link *e*, whereby, when the block I is slid forward in line with the trunnions *g g*, by depressing the treadle the pitman will cease working, substantially as described.
- 10 2. The combination of pivoted lever F, connected to the main driving-shaft of a mortising-machine, slide I, mounted thereon, and connected to the pitman C by rod *e*, with treadle L, connected thereto by toggle-lever K

and slotted link *m*, substantially as shown and 15 described.

3. The combination, with the slide I, toggle-lever K, and treadle M, of the adjustable link 20 *m*, connecting the treadle and toggle-lever, substantially as described.

In testimony that I claim the foregoing I have hereunto set my hand this 28th day of April, 1882.

HENRY FEYH.
